GRAIN STOOKER

Donald MacLean, Middlechurch, Manitoba,
Canada

Application August 18, 1936, Serial No. 96,692

7 Claims. (Cl. 56—410)

This invention relates to improvements in grain stookers and an object of the invention is to provide a device of the character herein described which is designed to operate in conjunction with a binder and to receive sheaves therefrom, said sheaves being formed into stooks which are afterwards deposited on the ground without compressing or scattering.

A further object of the invention is to provide a device of the character herein described which may be adjusted to form stooks equally successfully from grain of different lengths.

A further object of the invention is to provide a device of the character herein described which will form stooks of various sizes.

A further object of the invention is to provide a device of this character which will operate successfully with sheaves of various sizes.

A further object of the invention is to provide a device of the character herein described which is equipped with a rearwardly moving belt which carries the stooks and travels at exactly the forward speed of the machine in order that no breaking of the stook will occur when it is deposited upon the ground.

A still further object of the invention is to provide a device of the character herein described which is economical to manufacture and will not easily become out of order.

With the above more important objects in view and such other minor objects as may appear as the specification proceeds, my invention consists essentially in the arrangement and construction of parts all as hereinafter more particularly described, reference being had to the accompanying drawings, in which:—

Fig. 1 illustrates a plan view of my improved type of grain stooker.

Fig. 2 is a sectional elevation taken on the line 40 2—2 Figure 1.

Fig. 3 shows a plan view of a further type of sheaf elevating device which may be used with my stooker.

Fig. 4 illustrates an elevational view of the same.

Fig. 5 is a detail view showing a method used to transmit motion from the horizontal lying shaft to the vertical shafts which operate the sheaf carrying belts.

In the drawings like characters of reference indicate corresponding parts in the different figures.

This invention consists of a framework 1 composed of side bars 2 in the form of angle irons 55 which are angulated downwardly as at 3. Boards

4 extend between the angle irons in the front portion of the device and provide a platform 5. Further angle irons are situated beneath the platform for supporting purposes and to add rigidity to the device. A deep aperture 6 is cut in the rear portion of the platform for a purpose presently to be explained and leaves side legs 7 on either side thereof.

At the rear of each of these side legs is attached a bearing 8 which carries a swivel wheel 9 mounted in a yoke 10. Further apertures 11 are provided on either side of the platform adjacent the forward end thereof and a long shaft 12 extends transversely beneath the platform being mounted in bearings 13. Upon the shaft are keyed drive wheels 14 and 14' provided with lugs 15 as illustrated.

Adjacent the wheel 14' which will be nearest the binder (not shown) is mounted a large sprocket wheel 16 for a purpose presently to be explained.

Situated adjacent the forward end of the machine and extending upwardly and laterally over the wheel 14' is a sheaf-carrying elevator 17 which consists of a framework 18 across the lower end of which extends a rotatable shaft 19 mounted within bearings 20. Fastened to this shaft between the bars 21, 22 and 23 is a pair of rollers 24 and 25. Similar rollers 26 and 27 are mounted upon independent shafts 30 and 31 carried by the forward ends of the bars 22 and 23 and 21 and 22 respectively. It should be noted that the bars 21 and 22 are somewhat longer than the bar 23 so that an aperture 32 is formed between the bar 22 and the roller 26.

Elevator belts 33 are mounted upon the rollers in the manner illustrated and the shaft 19 is provided with a sprocket wheel 34 at one end thereof to receive power from a binder or if desired, this power may be obtained from the driving wheel 14' of this device by any convenient method of power transmission.

Situated centrally upon the forward end of the platform 5 is the sheaf tipping mechanism 35 which consists of a stationary curved plate 35 upon the rear side of which are attached aligned bearings 36 which carry a shaft 37 therein. Pivotedly mounted upon this shaft is an angulated metallic strip 38 which is turned over the upper edge of the plate 35 and carries a movable tipping plate 39 at the end thereof.

This plate is formed with a rearwardly extending flange 40 attached to the lower edge thereof and the strip 38 is prolonged backwardly through an aperture 41 within the plate 35 and is securely

attached to the flange 40 to maintain it rigidly in position. Upon the forward side of the plate 35 is attached a protruding stud 42 and an opposing stud 43 is mounted upon the inner surface of the strip 38. Extending between these studs is a helical compressive spring 44 which serves to maintain the tipping plate and the flange in the position illustrated most clearly in Figure 2.

10 It should be mentioned that the spring 44 is light enough to allow the plate 39 to tip forwardly when a sheaf of grain falls upon the flange 40.

15 Positioned immediately below the flange 40 is a roller 45 mounted upon a shaft 46 carried in bearings 47 which are attached to the platform 5. This roller, it should be noted, is placed within an aperture 46' in the platform. A companion roller 48 is mounted upon a long shaft 49' which is carried in bearings 50, 51 and 52. Around the 20 rollers 45 and 48 is placed a travelling belt 49 which is supported intermediately upon a raised platform 50' which extends beneath the upper portion of the belt.

25 The outer end of the shaft 49 is provided with a pinion 53 which is securely attached thereto and engages with a further pinion 54 mounted upon a stub shaft 55 carried by the bearing 56. Upon the inner end of this latter shaft is mounted a sprocket wheel 57 in alignment with a sprocket 30 wheel 16 adjacent the drive wheel 14'. A sprocket chain 58 connects the wheels 57 and 16 in order to transmit motion from the drive wheel 14'.

35 Mounted upon the platform 5 adjacent the shaft 49' is a pair of standards 58 having rotatable shafts 59 extending therethrough. The lower ends of these shafts are provided with 45° helical gears 60 as shown most clearly in Figure 5 and engage with similar gears 61 mounted upon the 40 shaft 49'. With this arrangement, it will be obvious that rotation of the shaft 49' will cause the shaft 59 to also rotate. The upper ends of these latter shafts, it should be noted, are provided with sprocket wheels 62.

45 Integrally attached to, and extending centrally from the standards 58 are a pair of arms 63 which carry vertically disposed shafts 64 at the inner ends thereof. These shafts are provided with sprocket wheels 65 in alignment with the wheels 62 and sprocket chains 66 are passed therearound. A second pair of arms 67 on substantially the same level as the arms 63 extend centrally and rearwardly from the standards 58 and are also provided with vertical shafts 68 at the ends thereof. These latter shafts, it should be noted, are firmly secured to the arms and do not rotate as do the shafts 64.

50 Fastened to the upper ends of the shafts 68 are short links 69' the ends of which are received over the shafts 64 beneath the sprocket wheels 65. These links are designed to act as braces to help support the shaft 64.

Extending centrally and forwardly from the standards 58 are a still further pair of arms 69 which are bifurcated at the forward end thereof to form fingers 70 between the ends of which are mounted shafts 71 carrying rollers 72 thereupon.

70 These latter arms, it should be noted, are rotatably mounted upon the standards and are provided with short portions 73 integrally attached thereto which extend outwardly from the standards. To the end of the portions 73 are pivotally attached rods 74 which extend rearwardly and are fastened to hand levers 75

mounted upon short shafts 76 carried within bearings 77.

At the forward end of the machine in line with the standards 58 is a second pair of standards 78 to which is securely attached a pair of centrally extending arms 79 which carry vertically disposed shafts 80 at their inner ends, these shafts being each provided with rollers 81 mounted thereon and to the lower end of each roller is affixed a spoked rimless wheel 82 which is designed to urge 10 grain sheaves forwardly in a manner presently to be explained.

15 Rotatably mounted upon the standards 78 is a pair of rearwardly and centrally extending bifurcated arms 83 similar to the arms 69 which carry pivotally mounted rollers 84 at the ends thereof. Integral sections 85 of these arms extend past the standard 78 and are provided with rods 86 pivotally attached to the ends thereof. These rods extend rearwardly and are secured 20 to levers 87 similar to the levers 75 mounted upon the shafts 76.

25 It should here be mentioned that rollers 88 are fastened to the shafts 64 between the arms 63 and the links 69 and are designed to be rotated 25 by the chains 66. Around the rollers 88 and 81 are passed belts 89 which carry a series of vertically disposed slats 90 on the outer surface thereof.

30 The rollers 72 and 84 carried by the arms 69 and 83 respectively, are positioned between the two sides of the belt 89 and are designed to bear against the inner surface thereof as shown most clearly in Figure 1. Thus when the levers 75 and 87 are actuated, the rollers 72 by means of the 35 arms 69 and 83 can be made to adjust the distance between the opposing faces of the belts 89 and thereby vary the width of the passageway bounded by these two belts.

35 Mounted upon the shaft 76 adjacent the 40 pinions 53 and 54 is yet a third lever 91 which carries a bifurcated yoke 92 securely attached thereto. Between the ends of this yoke is pivotally mounted a small roller 93 and similar rollers 94 and 95 are mounted in alignment therewith upon shafts 94' and 94''. This latter shaft is carried by bearings 96 and is designed to extend across the inner end of the aperture 6. Around these three rollers is placed a band 97 and it will be obvious that tightening the band by actuating 50 the lever 91 will cause the roller 94 to rotate the rollers 93 and 94 which in turn revolves the shaft 94'.

55 Mounted upon the shaft 94' between the confines of the leg 7 of the platform, is an elongated 55 roller 98 and a second roller 99 in alignment therewith is mounted adjacent the mouth of the aperture 6 within bearings 100. Around these rollers is placed a discharge belt 101 which is supported upon a plurality of further rollers 102 60 carried by bearings 103. Pivotally attached to the vertical rods 68 is a pair of opposed, rearwardly extending, metallic strips 104, which are designed to embrace the stock in a manner to be explained.

65 Attached to the outer side of these strips intermediately along the length thereof, is a pair of outwardly extending rods 105 which are slidably supported within bushings 106 surmounted upon posts 107. Between the strips and the 70 bushings extend compression springs 108 which are designed to maintain the strips normally in the position illustrated in Figure 1.

75 Mounted upon either side of the belts 101 is a pair of vertical posts 109, the lower portions 75

110 of which are tubular and receive rods 111 therein. The elevation of these rods may be adjusted by set screws 112 which extend through the walls of the tubular portion. To the upper 5 ends of the rods are secured resilient arms 113, the ends of which are provided with an arcuate configuration as at 114.

Similar posts 115 are mounted adjacent the ends of the strips 104 and are also provided with 10 resilient arms 116 which are somewhat longer than the arms 113 and overlap in the manner illustrated. A pair of shorter arms 117 of a similar nature is secured to the upper ends of the shafts 68.

15 Extending across the mouth of the aperture 6 adjacent the belt 101 is a discharge plate 118 mounted upon a transversely extending shaft 119. The rear edge of this plate, it should be noted, is designed to drag upon the ground as the machine 20 is moved forwardly.

In Figures 3 and 4 of the accompanying drawings, I have illustrated a further type of sheaf elevating means. In this latter structure, I have provided a framework 120 consisting of a pair of 25 angulated arms 121 which carry shafts 122 mounted within bearings 123.

Rollers 124 are securely fastened to the shafts. Around these rollers is passed a belt 125 which carries a plurality of rows of curved fingers 126. 30 Positioned adjacent the upper end of the belt 125 is a downwardly extending chute 127 carried by supporting braces 128.

As the sheaves are thrown upon the fingers 126, they are elevated and dropped into the chute 127 35 from whence they are precipitated into the machine to be formed into a stool in the manner presently to be explained.

The construction of my improved type of stooking machine having been disclosed, the method 40 of operation thereof will now be presented.

This machine is designed to be used in conjunction with a binder and as the sheaves leave the binder, they are thrown upon the belts 33 which are moving upwardly due to the rotation of the shaft 19 by power received from the binder through the sprocket wheel 34. As a sheaf 129 reaches the upper end of the shorter belt, it tilts 45 downwardly, in the manner shown, and falls through the aperture 32. It should here be mentioned that the sheaves are always placed upon the belts 33 so that the heads thereof are pointing towards the rear of the machine and in this manner when they fall through the aperture 32, they will be standing upright.

50 Each sheaf will then strike the flange 40 which causes the plate 39 to tilt and strike the head of the sheaf, thereby forcing it into engagement with the spokes 82 which urge it between the belts 89. These belts are at this time moving rearwardly as is the belt 49 due to power received 55 from the drive wheel 14' and 14 through the shafts 49 and 59.

Each sheaf is therefore carried rearwardly in an upright position and is ultimately pushed upon 60 the discharge belt 101 which is at this time in a stationary position.

As further sheaves fall upon the belt 49, they accumulate and bear against the resilient arms 117 and ultimately distend these arms to move 70 into the space bounded by the strips 104 and the arms 113. When sufficient sheaves have been received within this space to form a stool, the lever 91 is pulled backwardly by an attendant to actuate the belt 101 and cause it to move in the direction indicated by the arrow. The stool then

distends the arms 113 and finally bears against the arms 116 which keep it closely packed until it slides down the discharge plate 118 onto the ground.

It should here be mentioned that an important feature of this device is the speed of travel of the belt 101 which is made exactly the same as the forward speed of the machine so that as a sheaf is moved by the discharge belt, it has no motion relative to the ground and therefore, as 10 it slides down the discharge plate, it possesses no tendency to break and scatter nor to compress.

If desired, the discharge belt 101 may be split centrally into two portions, thus forming two separate belts operating side by side. In the space between these belts may be mounted a short upright fin which flares outwardly adjacent the plate 118. With this arrangement, as a stool is being moved by the belts, it will be separated 20 into two sections which will lean against each other when deposited on the ground, thus forming a very firm stool.

The elevating means illustrated in Figures 3 and 4 operate in the same manner as that illustrated in the first embodiment and sheaves which are carried up by the fingers 126 fall into the chute 127 and are precipitated onto the flange 40 in an upright position to be carried forward in the manner already described.

It should be noted that sheaves of different size can be formed by permitting the strips 104 to distend against the pressure of the belt 108 to any desired extent.

In order to take care of short sheaves, the 35 posts 109 may be shortened by sliding the rods 118 down into the tubular portions 110 and thereby reducing the elevation of the resilient strips 113. This same procedure may be undertaken with the resilient arms 116.

In order that sheaves which are small in width may be gripped between the belts 89, the arms 65 45 and 83 may be rotated by the levers 75 and 87 respectively, to force the opposing faces of the belts 89 into closed relationship and reduce the width of the passageway therebetween.

From the foregoing, it will be apparent that I have provided an ingenious type of stooking machine which possesses an outstanding advantage over former machines of this character in 50 that stools which are expelled therefrom have no tendency either to compress or to scatter, thereby preventing collapse of the stools.

Since various modifications can be made in the above invention and many apparently widely different embodiments of same made within the scope of the claims without departing from the spirit and scope thereof, it is intended that all matter contained in the accompanying specification shall be interpreted as illustrative only 60 and not in a limiting sense and I desire only such limitations placed thereon as are specifically expressed in the accompanying claims.

What I claim as my invention is:—

1. Improvements in grain stookers comprising 65 a movably mounted framework, sheaf receiving and elevating means attached thereto, a movable sheaf carrying belt mounted beneath said elevating means, said elevating means being adapted to deposit a sheaf in an upright position upon 70 said carrying belt, vertical belts situated on either side of said carrying belt and a pivotally mounted tipping element designed to urge said sheaves into engagement with said vertical belts, means for actuating said sheaf elevating means, said 75

carrying belt and said vertical belts, a normally stationary discharge belt at one end of said carrying belt, a pair of lateral, horizontally disposed rollers, said discharge belt being mounted thereon embracing arms situated on either side thereof, a plurality of resilient arms extending partially thereacross, said carrying belt being adapted to deposit a plurality of sheaves upon said discharge belt between said embracing arms and said resilient arms to form a stock and means for imparting motion to said discharge belt to deposit said stock in unbroken formation upon the ground.

5. The device as claimed in claim 1 in which a discharge plate, designed to drag upon the ground, is situated at one end of said discharge belt.

6. The device as claimed in claim 1 in which said sheaf receiving and elevating means comprises a pair of belts movably mounted upon an inclined framework, one of said belts being of greater length than the other thereof.

7. The device as claimed in claim 1 in which the means for receiving and elevating said sheaves comprises a movably mounted inclined belt, sheaf carrying means upon said belt and a chute situated adjacent said belt to deposit said sheaves upon said carrying belt.

8. Improvements in grain stockers comprising a movably mounted framework, sheaf receiving

and elevating means attached thereto comprising a movably mounted inclined belt, sheaf carrying means upon said belt, a chute situated adjacent said belt to deposit said sheaves thereonto, a movable sheaf carrying belt mounted beneath said inclined belt, said inclined belt being adapted to deposit a sheaf in an upright position upon said carrying belt, vertical belts on either side of said carrying belt, and a tipping element designed to urge said sheaves into engagement with said vertical belts, means for actuating said inclined belt, said carrying belt and said vertical belts, a normally stationary discharge belt at one end of said carrying belt, embracing arms situated on either side thereof, a plurality of resilient arms extending partially thereacross, said carrying belt being adapted to deposit a plurality of sheaves upon said discharge belt between said embracing arms and said resilient arms to form a stock, and means for imparting motion to said discharge belt to deposit said stock in unbroken formation upon the ground.

9. The device as defined in claim 5 in which said sheaf carrying means comprises a plurality of fingers attached to said belt.

10. The device as claimed in claim 1, in which means are provided for varying the size of the passageway between said vertical belts.

DONALD MACLEAN. 30
